RAILWAY SPIKE

Filed Sept. 28, 1927

INVENTOR:

Frederick W. Stohr

BY David S. Carlson

ATTORNEY.

UNITED STATES PATENT OFFICE

FREDERICK W. STOHR, OF SOUTH ST. PAUL, MINNESOTA

RAILWAY SPIKE

Application filed September 23, 1927. Serial No. 222,655.

My invention relates to spikes of a type particularly useful in railway construction for securely holding rails to ties and also useful for other purposes such as holding structural steel or iron and heavy timbers together. The invention consists of certain improvements in the form and application of the spike as hereinafter fully disclosed and illustrated in the accompanying drawing, in 10 which,—

Fig. 1 is a top view of my improved spike.

Fig. 2 is a side elevation of my spike in operative position showing a rail flange secured by the spike to a tie, the said flange and tie being shown in section.

Fig. 3 is an elevation of the spike alone as looking toward the spike in Fig. 2 from the right.

Fig. 4 is a cross sectional view of the spike shank as on line 4—4 in Fig. 3.

Fig. 5 is a perspective view of a portion of a rail and tie, with one of my spikes driven part way into the tie.

Fig. 6 is a point end elevation of my improved spike.

Referring to the drawing by reference letters, A designates a railway rail with the usual base flange A' tapered toward its outer edge. B is a wooden cross tie of the usual 30 type well-known in railway construction work.

The spike comprises a shank C preferably of approximately circular shape in cross section (see Fig. 4) and having a tapered point C' with a plurality of downwardly directed notches C'' gradually enlarged to the tip and forming a cross-shaped end with chisel like extremities.

D are a number of upwardly facing approximately semi-circular ledges on the shank arranged alternately at diametrically opposite sides and above each of which the shank is tapered inwardly and downwardly to the inner part of each ledge. Each ledge, furthermore is sloped downwardly, and all ledges sloped in the same direction for a purpose presently to be described.

The head of the spike is formed integral with the shank and may be said to have two parts, namely an elongated flange F rounded

at one end as F', its opposite or rear end being at right angles to the sides, see Fig. 1. Directly over the shank and concentric therewith the head is further formed with a polygonal head H, preferably square, for 55 applying a bar wrench to turn the spike so that the longer part F' of the flange F engages the rail flange A' as in Fig. 2.

In the use or application of my improved spike it is started and driven into a tie just 60 outside of the rail flange, the same as other railway spikes, but its head is held longitudinally of, or rather in parallel relation to the adjacent rail flange edge (see Fig. 5), until the under side of the head flange engages 65 the rail, as indicated in Fig. 3. Then a suitable wrench (not shown) is applied to the square head H and the entire spike is given a quarter turn to bring the end F' of the head in on top of the rail flange. The spirally arranged ledges D, simultaneously act as threads forcing the spike slightly deeper and more solidly into the wood. I have illustrated these ledges sloped to correspond with the direction of right hand threads and it is 70 obvious that the fibre of the wood in which the spike is driven will wedge or work toward the tapered parts of the spike above each ledge, and form an effective resistant for any upward tendency of the spike which 75 may be caused by so-called pounding of wheels on the rail. In lower part of Fig. 3 and in Fig. 4 that part of the ledges which is highest terminates in a shoulder D', either 80 radial from the center of the spike or tangential. It is clear that after one of my spikes, with these shoulders, has been driven and turned as described to its rail holding

position, said shoulders will resist any reverse turning of the spike. This is because the 90 wood of the tie will naturally press into the cavity rearward of each said shoulder D' and the latter finds resistance against it.

I do not of course desire to be limited to any specific number or spacing of the shoulders D or other details referring to sizes, it being obvious that the spike for railway purposes must be approximately the same general dimensions as railway spikes now in use. For holding timbers of various sizes to struc- 100

tural steel flanges may require spikes of various sizes.

In Fig. 5 will be seen that the ledges D are diametrically opposite and on a diametrical center line parallel to the longitudinal center of the flange F. Thus when the spike is driven in and later turned the said turning movement causes the ledges to wedge into the cross grain of the wood.

10 I claim:

1. A spike having a shank formed with a pair of sides substantially straight and parallel, and a second pair at substantially right angles to the first composed of oppositely located, transversely staggered groups of longitudinally aligned shoulders, said shoulders presenting like helical surfaces inclined toward the entering end of the shank, the sides of the shank on which the groups 20 of shoulders are located being defined by straight portions running from the inner edge of one shoulder to the outer edge of the next higher and aligned shoulder.

2. The structure specified in claim 1 and spike rotation preventing means comprising a number of downwardly directed tapering and radial shoulders each formed by making a radial face at the top part of each said helical surface and extending downwardly 30 longitudinally of the spike toward the next lower helical surface.

In testimony whereof I affix my signature.

FREDERICK W. STOHR.
